HORN

Theodore J. Scofield, Jackson, Mich., assignor to
The Sparks-Withington Company, Jackson,
Mich., a corporation of Ohio

Application August 12, 1937, Serial No. 158,771

1 Claim. (Cl. 177—7)

This invention relates to improvements in a horn or warning signal operated by an electric motor of the magnetic type in which a vibratory diaphragm is supported between a pair of case or housing sections, and the objects of my improvements are, first, to provide a relay-operated switch in the circuit for the motor, said relay being adapted to be controlled by a manually operated switch whereby the relatively heavy current, necessary for operating a motor of the magnetic type, will not be passed through the manually operated switch; second, to form at least one of the diaphragm housing sections from a sheet metal stamping; and, third, to utilize a portion of the housing section, which heretofore has been cut out and discarded, to form a frame for the relay integral with the housing sections.

I attain these objects by the mechanism illustrated in the accompanying drawing in which:

20 Figure 1 is a transverse central sectional view of a horn or warning signal embodying the various features of this invention, taken substantially in the plane of the line 1—1, Figure 2.

25 Figure 2 is a plan view of the motor illustrated in Figure 1, with the cover removed.

Figure 3 is a perspective view of a portion of one of the diaphragm housing sections illustrating a relay frame formed from a portion thereof in accordance with this invention.

30 Figure 4 is a detail sectional view taken substantially on line 4—4, Figure 2, showing parts in elevation.

Figures 5, 6 and 7 are detail sectional views taken respectively on lines 5—5, 6—6 and 7—7,

35 Figure 4.

Figure 8 is a wiring diagram showing the electric circuit included in the present invention.

The signalling device, as shown more particularly in Figures 1 and 2 of the drawing, comprises two circular diaphragm case or housing sections 40 and 11 having a diaphragm 12 clamped between them by bolts or screws 13 passing through aligned holes provided in the marginal portions of the housing sections 10 and 11 and diaphragm 12.

45 These diaphragm housing sections 10 and 11 are, as shown, composed of sheet metal plates having their central portions 10' and 11' pressed laterally in opposite directions and arranged in opposite relation to each other to form a diaphragm chamber 14 between said sections. The front diaphragm housing section 10 is provided with a centrally disposed forwardly extending annular flange 15 to which is secured in any suitable manner, as by screw-threads 16, a horn proper or projector 11.

The rear diaphragm housing section 11 constitutes a mounting plate for an electric motor for operating the diaphragm 12. For this purpose the housing section 11 has the central portion 11' thereof provided with an opening 18 arranged substantially centrally thereof for the reception of a laminated frame 19 of an electro-magnet 20 therethrough. The frame 19 in this instance is a substantially rectangular shaped member and extends from within the chamber 14 adjacent the inner side of the housing section 11 outwardly or rearwardly through the opening 18. The frame 19 may be secured to the housing section 11 in any suitable manner as by laterally disposed feet 21 formed integrally with the frame and which are spot-welded to the inner side of the housing section. The frame 19 is provided with a pair of recesses or slots as indicated at 22, Figures 5 and 6, extending inwardly from the outer or rear side thereof and disposed transversely of the frame at opposite sides of the center thereof for supportably receiving the usually pre-formed field coil 23.

An armature 24 is mounted over the outer or rear face of the frame 19 and is operatively connected to the diaphragm 12, in this instance by a stud 25, adjustably clamped to the armature as indicated in Figure 1. The stud 25 extends inwardly or forwardly from the armature 24 through a centrally disposed opening 26 provided in the frame 19 and is connected to the central portion 30 of the diaphragm 12 by a nut 27 screw-threaded on the inner end of the stud 25 and suitable washers as indicated at 28 mounted on the stud at opposite sides of the diaphragm.

As is usual with this type of motor, an automatic circuit breaker or interrupter is provided for intermittently opening and closing the current for coil 23. This circuit breaker comprises a pair of contact arms 30 and 31 mounted in any suitable manner in a contact stack 32 connected to the housing section 11 at one side of the frame 19, the arms to be supported by said section in cooperative relation with each other and with the stud 25. The contact arms 30 and 31 are connected in the electric circuit for the motor and operated in the usual manner by the armature 24 and stud 25 to effect intermittent energizing and de-energizing of the field coil 23 in synchronism with the movement of the diaphragm 12 away from and toward the magnet frame 19 in the usual manner.

As indicated in the drawing, I have provided the outer or rear end portion of the stud 25 with a yielding support 34 which in this instance comprises a flat spring member 35 connected to the

stud 25 adjacent the outer or rear face of the armature 24 by a nut 36 and washer 37. The other end of the member 35 is supportedly connected to the rear diaphragm housing section 11 by a stud or post 38 secured in any suitable manner to said housing section at one side of the opening 18.

The opening 18 is usually formed by stamping out a portion of the plate from which the housing section 11 is made during the formation of said section, which stamped out portion has heretofore been discarded. In this instance, however, I utilize at least a portion of the member stamped out to form the opening 18, to form a frame 40 for supporting a relay 41. The relay 41 is so connected with the contact arms 30 and 31 that upon actuation of a manually controlled switch or horn button, the circuit through the electromagnet for the horn will be completed through the relay so as to avoid passing the heavy current required to operate the horn electromagnet through the manually controlled switch or horn button.

This frame 40 comprises a central body portion or plate 42 and a pair of laterally disposed arms 43 and 44 extending from opposite sides of said body portion. The body portion 42 is formed with one end thereof integral with the housing portion 11' at one end of the opening 18 and is pressed outwardly or rearwardly from said opening so as to extend from the housing section at substantially right angles thereto, as indicated in Figure 3. The arms 43 and 44 are pressed laterally from the body portion 42 to extend therefrom away from the opening 18 in spaced substantially parallel relation with each other. One of the arms 43 is utilized to form a core for the relay 41 and for this purpose has the relay coil 45 wound thereon intermediate the ends thereof, as indicated in Figure 7. A pair of insulating washers or plates 46 may, as shown, be mounted on the arm or core 43 at opposite sides of the coil 45. The inner plate 46 rests against a pair of shoulders 47 provided on the arm 43 in slightly spaced relation to the body portion 42, while the outer end of the arm or core 43 is upset, as indicated at 43', Figures 4 and 5, to hold the outer plate 46 in place on said arm.

The other arm 44 is utilized to support the armature 48 of the relay in cooperative relation with the outer end of the arm or core 43. This armature 48 is a relatively light member stamped, in this instance, from sheet metal and is connected at one end to the arm 44 by means of an L-shaped flat metal spring 49 which has one arm thereof connected to one end of the armature 48 in any suitable manner, as by rivets 50. The other arm of the spring 49 is connected to the arm 44 by a pair of screws 51. The spring 49 is electrically insulated from the arm 44 by insulating plates 53 positioned at opposite sides of the spring and sleeves 54 mounted on screws 51, as shown in Figures 4 and 7.

A terminal plate 55 is also clamped to the arm 44 by the screws 51 and is insulated from said arm and screws by the plates 53 and sleeves 54, the terminal plate 55 being mounted adjacent the spring 49 to be in electrical connection therewith. The terminal plate 55 has a lug 56 bent upwardly therefrom and which is connected to one end of the coil 45 of the relay 41 by a wire 56 secured to said lug by solder or other suitable means, as indicated in Figure 4. The terminal plate 55 has the outward end portion thereof provided with a threaded aperture 57 for the reception of a screw 58 by which one end of an electric wire or

conductor 59 leading from a suitable source of potential as battery B, Figure 8, may be connected. The other end of the coil 45 is connected in this instance by a wire 60 to a terminal screw or bolt 61 mounted on the upper or outer end of the body portion 42, said screw 61 being electrically insulated from the body portion on plate 42 by washers 62 and a sleeve 63 composed of insulating material and mounted on the screw, as indicated in Figure 5.

The rear diaphragm housing section 11 also has a lug 64 stamped outwardly or rearwardly therefrom adjacent the opening 18 and at one side of the frame 40, as indicated in Figure 3. This lug 64 is for the purpose of supporting a contact plate 65 which is secured to the lug in insulated spaced relation thereto by means of a supporting block 66 composed of any suitable insulating material and screws or bolts 67, as shown in Figure 6. The contact plate 65 has a contact point 68 secured thereto to be engaged by a similar contact point 69 secured to the outer or free end of the armature 48. The contact point 69 is normally maintained in slightly spaced relation to the contact point 68 by the spring 49. The terminal plate 65 is electrically connected with the upper or rigid contact arm 30 of the automatic circuit breaker by a wire 70 connected at one end to the screw or bolt 67 and at the other end to said contact arm by a screw 71, having screw-threaded engagement with a laterally extending terminal lug 72 connected to or formed integral with said contact arm 30, as indicated in Figure 2.

The circuit breaker, motor, and the relay just described may be enclosed by a cover 74, a portion of which is shown in Figure 1. This cover 74 is of usual construction, being an inverted cap-shaped member having the marginal edge thereof surrounding the rear housing section 11 and resting upon the marginal edge portion of the front housing section 10, the front housing section 10 being of a slightly greater diameter than the rear housing section 11 as shown in Figure 1, for supporting the cover 74.

The operation of the circuit for the electromagnet and relay will now be evident by referring to Figure 8 in connection with the remaining figures of the drawing. In the wiring diagram shown in Figure 8, the circuit for the relay 41 is provided with a manually operated switch or push button S which is connected with one side of the battery B by ground G. It will now be evident that when the switch or push button S is closed a circuit is completed from battery B through wire 59, terminal plate 55, wire 56 to relay coil 45; and thence through wire 60, switch S and ground G back to the battery B. The current thus passing through the relay coil 45 actuates the armature 48 and closes a circuit from the battery B through the wire 59, terminal plate 55, spring 49 to the armature 48 and thence through the contact points 69 and 68, plate 65 and wire 70 to contact arm 30; thence through contact points 30' and 31' to the contact arm 31, and through wire 76 to the field coil 23, wire 77 and ground G and thence back to the battery B. The consequent energization of the field coil 23 operates the armature 24 toward the frame 19 and breaks the circuit just described at the contact points 30' and 31'. When the circuit is thus broken at the contact points 30' and 31', current continues to flow but to a lesser amount through a resistance 78 shunted across the contact points 30' and 31' in a manner and for a purpose well understood in this art. The re-

sultant partial de-energization of the field coil 23 releases the armature 24, whereupon the circuit is re-established through the contacts 30' and 31' and the armature 24 is again drawn toward the frame 19. The action just described is rapidly repeated so long as the horn button S is depressed, resulting in a corresponding actuation of the diaphragm 12 and the emission of an audible warning signal through the projector 17.

10 It will be apparent that the relay construction hereinbefore described is equally applicable to a dual horn structure or to a structure wherein three or more horns are connected to operate together in lieu of the single horn installation illustrated by way of example. Furthermore, it will be obvious that the often used "two wire system" could readily be substituted for the one wire system shown and described in the instant application.

15 20 While the construction and operation described

herein are particularly simple, practical and efficient, it will be evident that various modifications and changes may be made therein without departing from the spirit of the invention as set forth in the appended claim. 5

I claim:

In a warning signal having a vibratory diaphragm and an electric motor means operatively connected with the diaphragm for vibrating the same, means supporting said motor and diaphragm in cooperative relation with each other including a mounting plate, said plate having an integral portion thereof pressed outward to extend laterally therefrom and provided with spaced members, one member being adapted to form the core of a relay for the motor circuit and the other member being adapted to form a support for the armature of said relay. 10 15

THEODORE J. SCOFIELD. 20
